MEANS FOR OPERATING PUNCH-GAGS.

1,074,900.

Specification of Letters Patent.

Patented Oct. 7, 1913.

Application filed March 10, 1913. Serial No. 753,271.

To all whom it may concern:

Be it known that I, WILLARD T. SEARS, a citizen of the United States, residing at Hartford, in the county of Hartford and State of Connecticut, have invented certain new and useful Improvements in Means for Operating Punch-Gags, of which the following is a specification.

This invention relates to means for operating punch-gags, among the primary objects of the invention being the provision of means of this character which is simple in construction and positive and certain in action.

In the drawings accompanying and forming part of the present specification I represent in detail one of the several advantageous forms of embodiment of the invention which to enable those skilled in the art to practice the same will be fully set forth in the following description. I do not restrict myself to this disclosure; I may depart therefrom in several respects within the scope of the invention defined by the claims following said description.

Referring to said drawings, Figure 1 is a diagrammatic, sectional elevation of a punch-press equipped with means for operating the gag thereof, in accordance with the invention. Fig. 2 is a cross section of a core member and circuit closing means thereof, and, Fig. 3 is a side elevation of the same.

Like characters refer to like parts throughout the several figures of the drawings, which are on different scales.

It is not uncommon, in a punch-press, to employ what is known as a "gag." The form and location of this gag do not concern the present invention which resides in a certain novel organization by which said gag can be operated. That is to say the gag can coöperate with any suitable part of the press although I prefer that it be associated with the punch or with the reciprocatory head with which said punch is connected. Said gag after the usual fashion has two positions, one an inoperative position and the other an operative position. When the gag is in the first mentioned position, the punch or tool cannot punch or cut through the work or stock notwithstanding the fact that the head is being reciprocated but when said gag is in its operative relation the reverse

will be the case. The foregoing as is understood is common in punch-presses.

My invention relates to means by which the gag of whatever construction it may be and wherever it may be situated, is moved into its respective positions, and comprises as to one of its broader aspects, a pair of motors, one of which when put in action is adapted to move the gag into effective or operative position while the other motor when put into action shifts said gag into inoperative position. The motors in question may be of any suitable type although I prefer that they be fluid-operable, for instance and as will be hereinafter described, electrically-actuated. One of these motors is manually controlled while the other is automatically governed and while this statement applies to either motor, I prefer that the one which moves the gag to operative position be manually-controlled and that the other be automatically controlled. As motors which meet all the conditions, I might cite solenoids as I have illustrated and will herein-after describe.

With the foregoing general statements it is now proper to describe that structure, one of many, comprising my invention shown in the annexed drawings.

In Fig. 1 I have represented portions of a punch-press of standard construction, and having the reciprocatory head 2 mounted on the framework 3, the punch or tool 4 carried by said head, and the gag 5 all of which parts may be in construction and mode of operation, like the corresponding parts shown in Letters Patent No. 770,655 granted September 20, 1904 to J. V. W. Reynders and myself, for which reason the same require no further description, unless it be to note that when the gag 5 is in or in the path of movement of the punch or tool 4, said gag is in operative or effective relation at which point the punch or tool will penetrate or punch through the stock while when said gag is back, the punch or tool will not pass through the stock, in that said punch when it encounters the work can telescope or pass into the chambered part of the head 2.

For advancing the gag 5 or moving the same to effective position, I have shown the solenoid 6, the solenoid 7 hereinafter more particularly described, presenting a convenient means for retracting said gag or shift-

ing it into inoperative position. The core for the solenoid 6 is designated by 8 while that for the solenoid 7 is denoted by 9 and as shown they are carried by the common core member 10 which is not always essential although of advantage, the inner end of said member 10 being rigidly connected in some convenient manner, with the gag 5.

Any suitable means may be provided for supplying the necessary current to the two solenoids for energizing the same, the two line wires 11 and 12 being shown for such purpose and connected with a main (not shown). From the line wire 11 the conductor 13 extends being connected to one pole of the solenoid 6 while the wire 14 leads from the other pole of said solenoid 6 to the conductor 12, being intersected by the switch or push-button 15. The said solenoid therefore has a local circuit of its own, said circuit being shown as open in Fig. 1 at which time the gag 5 and core member 10 are in their retracted positions where they were moved by the energization of the solenoid 7. It will be assumed that the head 2 is being reciprocated and that it is desired that the tool 4 should punch through the stock. To secure this the local circuit just described is closed by the manipulation of the push button or switch 15 thereby energizing the solenoid 6 and causing the same to attract or draw in its core 8 and consequently moving the core member 10 and gag 5 to the left in said Fig. 1 and said gag into its operative position or in solid engagement with the upper end of the punch 4.

As already stated the gag is automatically moved to inoperative position but as I have also already observed this may not be so in all cases. The solenoid 7 also has its local circuit and I prefer that this particular circuit be controlled at two points to thus prevent sparking. One of the breaks in the second circuit may be closed for instance by means connected with the reciprocatory head 2 while the other, for example, may be closed by means connected with the gag 5, the latter being of advantage in that said circuit is closed only when the gag is in operative relation.

As shown the wire 16 connects the conductor 11 with one pole of the solenoid 7, while the wire 17 connects the other terminal of said solenoid 7 with the conductor 12, said wire 17 being intersected by two gaps or breaks provided with terminals 18 and 19 respectively. It will be clear therefore that when the two sets of terminals or contacts 18 and 19 are simultaneously bridged the solenoid 7 will be energized to shift the gag into inoperative position, through the attraction of the core 9 and the drawing back of the core member 10.

One of the circuit closers for governing the circuit of the gag retracting solenoid 7

is preferably connected with the reciprocatory head 2 while the other is preferably connected with the core-member 10 and the same may vary radically although those shown and now to be described answer my purposes. Upon the upper end of said head 2 is a horn-like arm 20 to which is connected the circuit closing member 21 insulated from said arm in some suitable way as by the insulation 22. Fitting around the squared portion 23 of the core member 10 is the insulating block 24 to opposite sides of which are connected the bowed-spring contact-fingers 25 connected together by bolts or pins 26, and which are adapted respectively to engage the contacts or posts 19 when the gag 5 is in its advanced or operative position.

It will be assumed that the gag is in its inoperative position as shown in Fig. 1 and that the head 2 is in motion and that it is above the extreme of its low movement. To put the gag into operative position, the switch 15 will be thrown to close the circuit of the solenoid 6 as already set forth so that said solenoid will attract its core 8 and therefore shift said gag 5 into operative position. As the gag assumes its operative position, the contact fingers 25 engage the terminals or posts 19 thereby closing the circuit of the solenoid 7 at one break thereof whereby when the head 2 descends to the limit of its downward movement, said circuit can be closed by the circuit closer 21 bridging the contacts 18 at which point the said solenoid 7 will be energized to attract its core 9 and thereby draw back the gag 5 into inoperative position.

What I claim is:

1. The combination with the gag of a punch-press, of a motor for moving said gag into operative relation, a second motor for moving said gag into inoperative position, manually-operable means for rendering one of said motors effective, and automatic means for rendering the other motor effective.

2. The combination with the gag of a punch-press, of a motor for moving said gag into operative position, a second motor for moving said gag into inoperative position, manually-operable means for rendering the first mentioned motor effective and automatic means for rendering the second motor effective.

3. The combination with the gag of a punch-press, of an electric motor for moving said gag into operative position, a second electric motor for moving said gag into inoperative position, manually-operable means for effecting the energization of one of said motors, and automatic means for effecting the energization of the other of said motors.

4. The combination with the gag of a punch-press, a plurality of solenoids coöp-

- erative with said gag, manually-operable means for effecting the energization of one of said solenoids to move the gag in one direction, and automatically-operative means 5 for effecting the energization of the other solenoid to move said gag in the opposite direction.
- 10 5. The combination with the gag of a punch-press, a plurality of solenoids, a core member connected with said gag, the cores of said solenoids being mounted upon said core member, and means for effecting the energization of said solenoids in predetermined order.
- 15 6. The combination with the reciprocating head and with the gag of a punch-press, of a motor for moving said gag into operative position, a second motor for moving said gag into inoperative position, manually-operable means for putting one of said motors into action, and means co-operative with said head, for putting the other motor into action.
- 20 7. The combination with the gag of a punch-press, of a motor for moving said gag into operative position, a second motor for moving said gag into inoperative position, and means for rendering the two motors ef- fective in predetermined order one of said means being automatically-operative.
- 25 8. The combination with the gag of a punch-press, an electrically-operated device for shifting the gag in one direction, a second electrically-operated device for shifting said gag in the opposite direction, manually-operable means for closing the circuit of one 30 of said electrically-operated devices, and automatic means for closing the circuit of the other electrically-operated device at two points.
9. The combination with the reciprocating head and with the gag of a punch-press, of an electric motor for moving said gag into operative position, manually-operable means for closing the circuit of said motor, a second motor for moving said gag into inoperative 35 position, and automatic means connected with said head and with said gag for closing the circuit of the second motor at two points.
- In testimony whereof I affix my signature in presence of two witnesses.

WILLARD T. SEARS.
